CLAIM

We claim the ornamental design for a microtitration plate, as shown and described.

DESCRIPTION

FIG. 1 is a perspective view of the inventive microtitration plate;

FIG. 2 is a top plan view of the microtitration plate;

FIG. 3 is a right side view of the microtitration plate;

FIG. 4 is a rear view of the microtitration plate;

FIG. 5 is a front elevation view of the microtitration plate;

FIG. 6 is a left side view of the microtitration plate; and,

FIG. 7 is a bottom view of the microtitration plate.

The broken line indicia added to the FIG. 2 view is for purposes of showing the microtitration plate in an environment of use. The broken lines in FIG. 7 define the boundaries of the claimed design. In all depictions, the broken lines and areas within them form no part of the claimed design.
